(57) **CLAIM**

We claim the ornamental design for a blast lock handle with angled body, substantially as shown and described.

DESCRIPTION

FIG. 1 is a front elevational view of a blast lock handle with angled body showing our new design;

FIG. 2 is a front elevational view thereof;

FIG. 3 is a side elevation view thereof;

FIG. 4 is an opposite side elevational view thereof;

FIG. 5 is an end elevational view thereof;

FIG. 6 is an opposite end elevational view thereof; and,

FIG. 7 is a perspective view thereof.

The broken lines form no part of the claimed design.
